CLAIM

The ornamental design for a femoral component, as shown and described.

DESCRIPTION

FIG. 1 is a perspective view showing the front, top and right sides of the femoral component;

FIG. 2 is a front elevation view thereof;

FIG. 3 is a rear elevation view thereof;

FIG. 4 is a right side elevation view thereof, the left side elevation view being a mirror image thereof;

FIG. 5 is a top plan elevation view thereof; and,

FIG. 6 is a bottom plan view thereof.

1 Claim, 6 Drawing Sheets
